SAFETY CHAMBER FOR SUBMERGED VESSELS

Application filed May 17, 1928. Serial No. 278,431.

This invention relates to life saving devices for submarines or other vessels, and particularly to the provision in a submarine or other vessel of a buoyant chamber into which the crew may pass and which may be released from the hull of the ship and either float upward due to its own buoyancy or be hauled upward by a salvage ship.

The general object of the present invention is to provide a life saving device of this character which is practical, simple, may be readily applied to submarines and indeed to other ships, and which is provided with means whereby the location of the sunken 15 submarine or other vessel may be indicated upon the surface of the water.

A further object is to provide a life saving chamber or compartment on board a vessel having a detachable float or buoy which 20 has attached thereto a flexible air tube so that when detached the buoy may rise to the surface and air may be drawn through said tube to the compartment or safety chamber of the vessel.

25 A still further object in this connection is to provide a special form of valve which will prevent the inlet of water to the tube as the upper end of the tube and the buoy move to the surface of the water but will permit, 30 by an initial injection of air through the tube, the valve to pass into a receiving pocket where it will not obstruct the inlet of air through said tube.

Another object is to provide means whereby the buoy may be detachably engaged with the hull of the submarine and particularly to the upper wall of the safety chamber, which is flush with the deck so as to permit the men inside the safety chamber to release the buoy, 40 and in this connection to provide means whereby air may be pumped initially through the hose of the buoy to open the valve and then the air drawn downward from the surface and discharged from the pump into the 45 safety chamber.

Still another object is to provide means whereby the safety chamber is normally locked in place with its upper wall flush with the deck but may be readily unlocked from 50 within the chamber so that the safety chamber

may be drawn upward by hoisting chains on the salvage ship or may move upward by its own buoyancy, and in this connection to provide means whereby the too swift rise of the safety chamber may be checked or retarded.

A further object is to provide means whereby water may be allowed to enter the base of the safety chamber to thereby control its buoyancy and keep it balanced.

A still further object is to provide means whereby air may be allowed to flow into the space between the wall of the safety chamber and the wall of the compartment within which the safety chamber is normally located, 65 so that the hydrostatic pressure allowed to enter around the chamber will permit the safety chamber to move upward under its buoyancy.

Other objects will appear in the course of 70 the following description.

Our invention is illustrated in the accompanying drawings, wherein:—

Figure 1 is an elevation of a salvaging vessel and a submerged vessel having our improvements applied thereto and showing the buoyant chambers rising to the surface;

Figure 2 is an enlarged vertical section partly in elevation of the compartment and the chamber therein, the buoy being locked 80 to the top of the chamber;

Figure 3 is a cross sectional view on the line 3—3 of Figure 2;

Figure 4 is an elevation of one end of the float, the top being shown in section;

Figure 5 is a detail view of the air valve.

In the drawings, A designates a submarine or other vessel, it being understood that while we have designed this particularly for submarines that we do not wish to be limited thereto. The submarine is provided at one or more points in its length, preferably at two points, with a compartment, designated 10, which extends upward approximately to the deck 11. This compartment at its upper 90 end is braced by an angle iron 12. The deck 11 is formed with an opening, which is circular or rectangular in cross section, depending upon the transverse section of the compartment 10 and the enclosed chamber, and 100

depending below this margin of the deck is the annular flange 13 constituting a casing within which is disposed packing 14.

Disposed within the compartment 10 is the safety chamber 15. This safety chamber is closed at its upper end by means of a horizontal wall 16 which is adapted to close the opening in the deck and extend over the margin of the deck, that is, to the flange 13, as at 17. This upper wall 16 is also formed with a depending, angular flange 18 apertured for the passage of locking bolts 19. There are as many of these bolts as desired, all the bolts extending toward the center of the compartment and being there connected to a gear wheel 20 mounted upon this upper wall, this gear wheel being engaged by a pinion 21, in turn operated by the hand wheel 22. Any other suitable gearing for rotating the gear wheel 20 may be used.

The locking bolts are pivotally connected at their inner ends to this gearing so that when the gear 20 is turned in one direction the bolts will be projected and when turned in the other direction the bolts will be retracted. When projected, the bolts lock the upper end of the chamber 15 to the compartment 10 and to the deck by penetrating the packing 14. When withdrawn, the chamber 15 may move upward through the opening in the deck.

For the purpose of lifting this chamber 15 by means of cables from a salvage ship, as shown in Figure 2, hoisting irons 23 are attached to the upper wall 16, this upper wall being relatively thick and strong and the chamber 15 being rigidly connected to this upper wall and being provided with suitable bracing means 24 of any desired character.

Disposed upon the wall 16 is a buoy 25 having at its opposite ends the threaded sockets 26. Locking bolts 27 pass upward through the wall 16 through packing and have swiveled engagement with this wall, the upper ends of these bolts being screw-threaded to engage the sockets 26 and the lower ends of the bolts having handles 28 whereby the bolts may be turned to release their engagement with the buoy and permit the buoy to float upward. Beneath the buoy there is supported an air hose basket 29 within which is coiled or laid the air hose 30. This is, of course, tubular and may be of any suitable character. The upper end of this air hose is connected by a coupling 31 to a valve casing or head 32 whose structure will be now described.

The coupling member 31 has screw-threaded engagement with the head 32 and the interior of this head is recessed for a removable seat 33. The head is longitudinally bored, as at 34, this bore extending laterally into a valve receiving chamber 35. Normally disposed upon this seat 33 is a globular valve 36 which is capable of being forced up the bore 34 and laterally from the curved ex-

tremity thereof into the pocket 37 formed in the chamber 35. This pocket is formed with a drainage opening 38 to carry off water which may enter through the air holes 39 in the top of the casing. The base of the valve body is formed with an outwardly projecting flange 40 which prevents the hose from pulling through the air tank buoy. The hose 30 is engaged with the coupling 31 by any usual or suitable means.

The inner end of the hose is connected to a pipe fitting 41 extending through the cover 16 and into the chamber 15 and is provided with an air line control valve 42 to which a flexible connection 43 may be attached, this extending down to an air pump 44 of any suitable character and actuated by any suitable means as, for instance, by an electric motor connected to a storage battery or it may be hand operated. This air pump should have an inlet and an outlet and is for the purpose initially of forcing air up the pipe 30 and out through the head 32 to lift the valve 36 when the buoy has risen to the top of the water and is floating upon the surface so that the valve will be forced up and into the pocket 37. Of course, while the buoy is rising, the valve 36 prevents the entrance of water into the interior of the pipe.

When the valve 36 has been forced from its seat into the pocket 37, the air pump 44 is then used to withdraw air from above the surface of the water, down through the pipe 30 and pipe 43 and force it into the interior of the safety chamber 15. The safety chamber 15 is provided with a floor 45 and below this floor there is provided a storage compartment 46 within which food, water, implements and other material may be stored, and entering this compartment is a valved pipe 47 whereby to permit the inlet of water to the interior of the compartment to thereby regulate the buoyancy of the safety chamber. The cover 16 is also provided with an inlet pipe 48 which passes down through the cover and through the side wall and opens into the space between the compartment wall 10 and the shell of the chamber 15 and is provided with a valve 49 whereby water may be allowed to enter the space between the chamber 15 and the compartment wall 10 so as to permit the hydrostatic pressure to be exerted upon the chamber 15 to permit it to float or rise from the compartment 10, this being controlled, of course, from the inside of chamber 15.

Preferably, and for the purpose of preventing too swift a rise of the safety chamber to the surface of the water, we provide a brake. As illustrated, a reel 50 is provided upon the hull of the submarine at any convenient point and a cable 51 is wound upon this reel and extends upward through the floor of the compartment 10 and through the floor of the safety chamber. We have illus-

trated a friction brake 52 carried upon the reel and bearing against the cable to restrain its upward movement.

It is to be understood that a spring brake, 5 a hydraulic brake or brake of any other character may be used in place of the brake shown, the idea being that the brake will restrain the too rapid upward movement of the safety chamber when released from within the compartment 10. The safety chamber is provided with a hinged or sliding door 53 and with a foul air discharge pump 54 of any suitable character acting, when started, to take the foul air from the interior of the 15 chamber and force it out through the side of the chamber so as to permit the injection of fresh air through the pipe 30. This pump may be actuated by the same means as is used for actuating the pump 44. A bilge pump 20 may also be disposed within the compartment 46 for the purpose of discharging any water that may seep into the compartment or into the safety chamber.

This device provides means by which men 25 entrapped in a sunken submarine or other vessel can liberate themselves and can be assured of a plentiful supply of fresh air during the period of submersion. If the necessity arises, the imprisoned men can assemble 30 in these chambers, close the water-tight doors and, by liberating the tank or buoy 25, the air hose is carried to the surface and then air may be withdrawn through this hose into the chamber 15, while the foul air is discharged 35 by the foul air pump 54.

If, after a period of waiting, the entrapped men feel that assistance is not available, they can release the locking bolts 19 and thus release the entire chamber from its position in 40 the submerged vessel. After the flooding valve 49 has been opened, water will be admitted around the chamber and create the necessary pressure to float it and the chamber will immediately rise to the surface. This 45 rise may be regulated by the valve 47 admitting water to the chamber as ballast or it may be regulated by the brake action on the cable 51.

The buoy serves two purposes, first to carry 50 to the surface the air lines, and second to act as a detector for submarines in distress. The valve prevents water from entering the air hose during submersion but readily admits air when the ball is dislodged from its seat by 55 air pressure from within the chamber. The air hose is to be coiled beneath the buoy in such a manner that it will not be obstructed in its ascent, the container or basket 29 being provided with drainage holes 29^a whereby 60 to drain out any water when the basket has risen with the submarine. The top wall or roof of the chamber 15 will, of course, be provided with a manhole 56 detachable from within the chamber whereby exit may be 65 made from the chamber after the chamber

reaches the surface. In the event it is found the safety chamber will not have sufficient buoyancy to rise to the surface, the auxiliary hose may be inflated by compressed air as, for instance, by compressed air tanks within the chamber itself. However, a chamber 70 ten feet across and of the same height would have a lifting force of some twenty tons so it is not believed it would be ever necessary to use any auxiliary means for increasing the buoyancy of the chamber. 75

The safety chamber should be constructed from material heavy enough to withstand the water pressure at sufficient depth and it should be sufficiently braced on the inside to prevent destruction by pressure. Of course, the chamber should be provided with emergency rations, flashlights, compressed air tanks or other auxiliary devices which may be necessary. 80

It is desirable to provide means whereby a diver may release the locking bolts 19, and to this end the shaft upon which the operating wheel 22 is mounted is extended through the wall 16 and provided with a hand wheel 22^a 85 so as to permit the diver to release the bolts in case for any reason the chamber should not rise from its place in the hull of the submarine. In order that the diver may observe whether any men are within the chamber before releasing the bolts, one or more glass plates 16^a are disposed within the wall or top 90 16 so that the diver may look into the interior of the chamber. 95

While we have illustrated this device as being applied to a submarine, and while this safety device is particularly designed for submarines, yet it is obvious that it might be applied to other vessels. It is also obvious that many minor changes might be made in the details of construction and arrangement of parts without departing from the spirit of the invention as defined in the appended claims. 100

We claim:-

1. The combination with an air hose connected at one end to a submersible vessel and connected at its other end to a buoy, that end of the air hose carried by the buoy being provided with a valve casing in the form of a head and formed to provide a centrally disposed bore, a chamber into which the bore opens, the chamber being provided with a pocket depressed below the mouth of the bore and having air openings in its outer walls, and a valve normally resting upon said seat 110 and held thereto by pressure of water but adapted to be blown from the seat and into said pocket by a blast of air directed upward through the air hose and through said bore. 115

2. In a vessel, a compartment opening 120 through the deck of the vessel and having upwardly flaring side walls, a safety chamber disposed within the compartment and less in diameter and length than the compartment and having a roof having water tight engage- 125

ment with the deck and closing the opening therethrough, the wall of the compartment adjacent the deck being formed to provide an annular recess filled with packing material, bolts projectible from the upper end of the safety chamber into said packing material to thereby lock the safety chamber to the deck, means disposed within the safety chamber for operating said bolts, a buoy detachably mounted upon the top of the safety chamber exterior thereto and having an air hose carried thereby at one end and extending into the safety chamber, means operable from within the safety chamber whereby the buoy may be released, an air pump within the safety chamber connected to the air hose, a pipe leading from the exterior to the top wall of the safety chamber downward through the safety chamber and into the space between the safety chamber and the wall of the compartment and a valve in said pipe whereby water may be admitted to said space.

3. In a vessel, a compartment opening through the deck of the vessel and having upwardly flaring side walls, a safety chamber disposed within the compartment and less in diameter and length than the compartment and having a roof having water-tight engagement with the deck and closing the opening therethrough, the wall of the compartment adjacent the deck being formed to provide an annular recess filled with packing material, bolts projectible from the upper end of the safety chamber into said packing material to thereby lock the safety chamber to the deck, means disposed within the safety chamber for operating said bolts, a buoy detachably mounted upon the top of the safety chamber exterior thereto and having an air hose carried thereby at one end and extending into the safety chamber, means operable from within the safety chamber whereby the buoy may be released, an air pump within the safety chamber connected to the air hose, a pipe leading from the exterior to the top wall of the safety chamber downward through the safety chamber and into the space between the safety chamber and the wall of the compartment, a valve in said pipe whereby water may be admitted to said space, and means including a reel mounted upon the vessel and a line or cable carried by the reel and extending into the compartment and engaging with the body at the lower end of the safety chamber, permitting the safety chamber to move upward when released under the action of buoyancy but preventing the safety chamber from becoming a derelict.

In testimony whereof we hereunto affix our signatures.

ALBERT G. JOHNSON.
CHARLES W. DEWING.
